CONTAINER

Hiram McCarty, Cleveland, Ohio

Application March 15, 1935, Serial No. 11,234

1 Claim. (Cl. 220—1)

This invention relates to a container provided with an accessory cup which is firmly secured to the underside of the container cap, and which can readily be detached and replaced. The 5 object of the invention is to provide a convenient means for carrying a drinking cup as a component part of the container.

The invention will be readily understood from the following description of the accompanying 10 drawing, in which:

Fig. 1 is a side elevation of the liquid container.
Fig. 2 is a section taken on lines 2—2 of Fig. 1.
Fig. 3 is a sectional view of the container cap and attached cup.

Fig. 4 is a side elevation of the cup.

Fig. 5 is a bottom plan view of the cap.

Fig. 6 is a bottom plan view of the cup.

Referring to the drawing: a container 10 of a cylindrical form is shouldered at 11 to form a neck 12; a flanged ledge 13 projects outwardly from the neck 12 near its center, and the neck above said ledge 13 is threaded at 14. A cap 15 which is threaded at 16 and grooved at 17 has inwardly projecting opposing flanges 18 and 19, undercut at 20 and 21.

A cup 22, having a shouldered base 23 from which projects a pair of ribs or lugs 24 and 25 is securely mounted by means of said lugs 24 and 25 within the cap 15; the ribs 24 are pressed down within the spaces 26 between the flanges 18 and 19 and the cup 22 is then turned until said lugs 24 and 25 are in the undercuts 20 and 21 between the flanges 18 and 19 and the body of the cap 15. The cap is then screwed down

upon the threaded portion 14 of the neck 12. Thus the cap 15, containing the cup 22, may be removed from the container 10, liquid from said container may be poured within the cup 22, which may be detached from the cap 15 or left within 5 the cap as desired. The cup is carried within the container as shown in Fig. 2. A washer 27 inserted within the groove 17 prevents leaking as the cap is screwed securely upon the neck of the container.

While certain features of my invention are more or less specifically described, I wish it understood that various changes may be resorted to within the scope of the appended claim, and furthermore that the materials and finish of the 15 several parts employed may be such as the varying conditions of use may demand.

I claim:

A container having an externally threaded neck, a screw cap fitting over and engaging the 20 threads of the neck, the inside of the top of the cap having spaced undercut flanges projecting therefrom, and a cup detachably connected to and within the cap, the side wall of the cup being spaced from the side wall of the cap, whereby the 25 cup is adapted to enter within the said neck when the cap is screwed thereon, the bottom of the cup fitting against the inside of the top of the cap, said bottom having spaced circumferential flanges in the plane of said bottom and en- 30 gageable under the said flanges by a turning movement, to hold the cup attached to the cap.

HIRAM McCARTY.
